DESIGN FOR A BUILDING VENTILATOR SHIELD

Ellsworth W. Cutshall, Houston, Tex.

Application May 2, 1942, Serial No. 106,778

Term of patent 14 years

To all whom it may concern:

Be it known that I, Ellsworth W. Cutshall, a citizen of the United States, residing at Houston, in the county of Harris and State of Texas, have invented a new, original, and ornamental Design for a Building Ventilator Shield, of which the following is a specification, reference being had to the accompanying drawing, forming part thereof.

In the drawing:

Fig. 1 is a front elevational view of a building ventilator shield showing my new design.

Fig. 2 is a top plan view.

Fig. 3 is an end elevational view.

Fig. 4 is a front perspective view thereof.

I claim:

The ornamental design for a building ventilator shield, substantially as shown.

ELLSWORTH W. CUTSHALL.
